In the Union of South Africa July 7, 1944

5 Claims. (Cl. 108—1)

1

This invention relates to concrete roofs; the term concrete being used in this specification to include any appropriate material that is moulded in a plastic condition and subsequently sets or is caused to set as a solid mass.

It is customary to construct flat concrete roofs both by the assembly of pre-cast components, including beams and slabs; and by moulding the whole roof in position from plastic concrete.

In the case of pitched roofs constructed wholly or partly of concrete the present practice includes the procedure of pre-casting all the components including pre-cast rafters, hoisting said components into position and there assembling them. It also includes the procedure of moulding a horizontal ceiling slab or horizontal beams in place; pre-casting the components—including rafters—that support the roof covering, pre-casting the roof covering, hoisting the separate pre-cast elements into position and there assembling them.

An object of the invention is to cheapen and simplify the construction of a pitched concrete roof by moulding plastic concrete in position.

The present invention consists in a pitched roof comprising a number of members, herein referred to as rafter members, that are spaced apart horizontally. Such rafter members are constructed to perform the function of supporting roof covering at the pitch inclination above spaced roof supporting means such as walls. The roof further comprises web formation that extends between and connects said rafter members; and both the rafter members and the web formation are formed of concrete moulded in position in the roof.

The form of the web formation may be varied. In one form it consists of a ceiling slab supported on the roof supporting means and extending between the lower parts of the rafter members. In another form it is the roof covering, supported by the rafter members beneath it. In another form the web formation consists of a number of vertical stabilizing webs extending from one rafter member to the other.

In most forms of roof according to the invention the rafter members extend in the direction in which the roof is inclined and rest at their ends directly or indirectly on the spaced walls or equivalent roof supporting structure. The rafter members of the invention are usually shaped to have the general triangular form in outline as an ordinary roof truss or principal. They may be solid triangles but it is preferred to core out portions within the triangular pe-

2

riphery; and the coring may be arranged to produce a monolithic rafter member having a close resemblance in shape to the ordinary built-up truss comprising rafters, a king post, a tension chord, and struts.

The roof covering that is supported by the rafter members may be of any desired kind of sheet material and where necessary purlins are mounted on the transverse rafter members to support such sheet material. However it is a desirable feature of the invention that the roof covering also is moulded in position on the rafter members; and preferably so as to be monolithic with said members.

15 The invention further consists in a process of erecting a pitched roof which comprises concrete roof covering cast on supporting structure such as rafter members above specified. Said process consists in erecting deck shuttering for the roof covering, and casting the roof covering on said deck shuttering while leaving aperturing in the roof for the extraction of the deck shuttering. The deck shuttering is then lowered to part it from the cast roof covering, and the deck shuttering is withdrawn piecemeal through the aperturing.

15 The aperturing through which the shuttering is withdrawn may be at the ridge of the roof; and this is particularly the case when the above-mentioned ceiling slab provides eaves soffits. 30 Said ridge aperturing is subsequently closed by placing ridge covering structure in position.

Examples of roof structure according to the invention are shown in the accompanying drawings in which—

35 Figure I is a perspective view showing a portion of the walls and the concrete pitched roof of a building.

Figure II shows the same, but with rafter members of a different form.

40 Figure III shows a roof with a hipped end.

Figure IV shows a roof without a ceiling slab.

Figure V shows a modification of the structure that supports the roof-covering.

45 Figure VI shows a lean-to roof.

Figure VII shows shuttering for moulding the rafter members.

Figure VIII shows a core block.

Figure IX shows shuttering for moulding the roof covering.

50 Figure X illustrates the removal of shuttering from the interior of the moulded roof.

Referring to Figure 1, 2, 2, indicate walls of the building and 3 indicates a concrete ceiling slab moulded in place and so as to be supported

by the walls 2. 4 indicates a number of rafter members moulded in position and extending upwardly from the said slab 3. The said members 4 are in outline of the same general triangular form as an ordinary timber roof truss and they perform the same functions as such a truss; that is they act as beams spanning the walls 2 and provide the sloping upper edges 5 on which roof covering 6 is supported at the pitch angle of the roof. The roof further includes said roof covering 6, which is a concrete deck sloping down two ways from the ridge 7 and made of concrete moulded in position.

Included in the roof shown, are the gables 8 which in the well known manner constitute a portion of the gabled walls 9 of the building and are not part of the present invention. During the moulding of the members 4, reinforcement 10 is left projecting from their upper edges 5 for uniting the moulded roof covering 6 to them. Preferably also apertures such as 11 are cored out to give access to or between the several bays 12 into which the roof space is divided.

Figure II shows another form of the roof in which the cored aperturing is so shaped that each rafter member 4 has the same general appearance and formation as an ordinary roof truss, so as to comprise elements 13, 14, 15, 16 corresponding respectively to the rafters, the tie, the king post and struts of a built-up truss, all such elements 13 to 16 being moulded in position from plastic material and so as to form a monolith.

Figure III shows much the same roof as Figure I but with a hipped end formation, including the half rafter members 17, and the hip rafters 18 meeting the full rafter member 4 at the ridge 7; and the jack rafter members 19 associated with the diagonal hip rafter members 18.

Another form of the roof shown in Figure IV, differs from that of Figure I by the omission of the ceiling slab 3; and by the members 4 being supported directly on the walls 2. This figure also shows the web formation as vertical and longitudinal webs 20 extending between the rafter members 4 and forming with the latter a cellular formation which combines lightness with considerable stiffness.

In Figure V, the Figure I arrangement is modified by omitting the transverse members 4 and substituting for them a number of longitudinal walls or ribs 21. The rafter function of supporting the roof covering at the pitch angle is in this case exercised by the combination of the several walls 21 which for that purpose form a series progressively increasing in height from the eaves 22 to the ridge 7. By extending lengthwise of the roof, said walls 21 perform the additional function of the purlins in an ordinary roof.

Figure VI shows a lean-to type of roof, which is structurally and functionally equal to a longitudinal half of Figure I.

Roofs according to the invention are erected with the aid of shuttering; and a typical method of using the shuttering is illustrated in Figures I, VII, IX and X.

The ceiling slab 3 is moulded in place by spreading plastic concrete on deck shuttering which is erected for the purpose and is afterwards removed. A shuttering structure capable of rapid erection and removal is shown in Figure I. Recesses 23 are provided at the tops of the walls 2; and bearer bars 24 are placed in said recesses 23 to span the space between the walls. Deck shuttering 25 of any suitable kind is mounted on said bars 24, to provide the moulding surface 26, and

shields 27 are placed over the recesses 23 to keep concrete out of the latter. Thereupon the plastic concrete is spread over said surface 26 to form the slab 3. When the concrete has set, the bars 24 are withdrawn endwise, permitting the deck shuttering 25 to fall or to be prised away from the concrete.

The recesses 23 are deep enough to enable the moulding surface 26 to be brought level with the upper surfaces 28 of the walls 2 or such other level as desired above the base surfaces 29 of the recess 23. To facilitate the endwise withdrawal of the bars 24, it is preferred to elevate them above the base surfaces 29 of the recesses 23 in a manner which permits them to be dropped before being moved endwise. For this purpose they are shown as supported on wedges 30 that can be knocked out of place to drop the bar.

The intermediate bearer bars 24 are shown of T section with their cross flanges 31 below, forming horizontal shelves on which separate shuttering panels 32 are loosely rested.

The end bearer bars 24a are of angle section in order that their vertical elements 33 may lie flat against the end walls 9. The advantage of using panels in this way between bearer bars is that the deck shuttering can be erected by building up a number of small units, individually capable of being handled; and the shuttering can be disassembled in the same advantageous manner.

After the ceiling slab 3 is poured, shuttering is erected on it for moulding the members 4 (Figure VII). In the example illustrated, the shuttering is of the kind described in my application Serial No. 577,898, now Patent No. 2,518,186, dated August 8, 1950. It comprises pairs of templet bars 34 which are laid on the ceiling slab 3 and are connected and spaced apart by ties 35. Shuttering panels 36 are provided which are similar to those described in the specification of my application Serial No. 583,269, now Patent No. 2,447,670, dated August 24, 1948, except that they are triangular to conform to the gable shape of the members 4. The panels and the templet bars are formed with the interengaging edge formations 37, 38 by which the panels are retained in the upright position. During the erection of the shuttering panel cores 39 are inserted between them to form the apertures 11 and further cores 40 are inserted to form the gaps 41 at the edges 5 of the members 4, to be described hereafter. The upper ends of the panels 36 are tied together by spring clips 42.

The members 4 having been moulded in place between the panels 36, the shuttering for moulding them is dismantled and the cores 39 and 40 removed. The cores 40 (Figure VIII) leave the gaps 41 in the upper edges 5 of the members 4, (Figure IX) arranged to receive round bars 43, that are preferably steel tubes and that support the deck shuttering 44 on which the roof covering 6 is moulded. Each gap 41 accordingly provides a lower recess 45 in which the bar 43 lies stably by gravity and an upward extension 46 from said recess. The depth of the gap 41—below its open mouth 47—at the recess 45 is equal to the diameter of the bars 43 and the thickness of the deck shuttering 44, so that the latter is supported with its upper surface 48 level with the sloped edges 5 of the members 4. In the extension 46 the depth below the mouth 47 is rather greater but so that the base surface 49, connecting the recess 45 to the extension 46, slopes upward to some

5

extent. At least two such gaps 41 are formed on each downwardly sloping edge 5 of the members 4.

In preparing for the moulding of the roof covering 6, the round bars 43 are laid to extend over the several gaps 41 of the different members 4 in the same horizontal series and to seat in the recesses 45. Deck shuttering 44 of such width as to fit neatly between the members 4 is laid on said bars 43 and the mouths 47 of the gaps 41 are shielded against the entrance of concrete by covers 50 of sheet material.

Plastic concrete is then spread over the deck shuttering 44 and the exposed edges 5 of the members 4. When the concrete has set the round bars 43 are rolled up into the recess extension 46 thereby allowing the deck shuttering 44 to drop or to be prized away from the underside of the hardened roof covering 6.

The deck shuttering 44 is withdrawn piece-meal from the interior of the roof for re-use, if it is suitable for such re-use, through openings provided for that purpose. In the example shown in Figures I and IX, the shuttering extends beyond the walls 2 of the building to provide the eaves of the roof and can therefore be withdrawn downward after separation from the roof covering. If the ceiling slab 3 is extended over the walls 2 to form an eaves soffit 51 Figure X, gapping 52 is left at the ridge of the roof for the withdrawal of the deck shuttering 44 upwardly. The missing ridge structure is afterwards completed as by ridge capping 53.

An important object of the invention is the construction of the roof as a monolithic structure combining light weight with stiffness as a girder.

When both the ceiling slab and the roof covering are moulded in position, the cross section of the roof resembles an I section girder; of which the ceiling slab 3 and the roof covering 6 are the bottom and top flanges and each rafter member 4 is the vertical element.

In order to utilize such girder formation to minimize the thickness of the concrete, it is important that the structure should be rendered monolithic to a high degree, as for instance by proper use of reinforcement to bond such sections together. In particular the reinforcement includes elements such as 54 Figure I, that closely unite the slab 3 and the members 4;

6

and the elements 10 that unite the roof covering 6 to the members 4.

I claim:

1. The process of erecting a pitched roof with a cast-on roof covering, which comprises the steps of supporting a plurality of longitudinally extending bars of circular section on the lower portions of bearing surfaces that diverge from the plane of the roof to be erected toward the ridge of the roof, positioning deck shuttering for the roof covering on said bars, casting the roof covering on said shuttering while leaving an opening in the roof for extraction of the deck shuttering, rolling the bars laterally along the bearing surfaces toward the ridge, lowering the deck shuttering to part it from the cast roof covering, and withdrawing the deck shuttering through the opening.
2. The process as set forth in claim 1 wherein the opening is formed at the ridge of the roof.
3. The process as set forth in claim 1 wherein the opening is formed at the ridge of the roof and further including the step of closing the opening after the shuttering has been withdrawn.
4. The process as set forth in claim 1 wherein the opening is formed adjacent the base of the roof.
5. The process as set forth in claim 1 further including the steps of lowering the bars after the shuttering has been withdrawn through the opening and withdrawing the bars from their bearing surface.

ROY WILLIAM RUMBLE.
